[57] ABSTRACT

A method of manufacturing a fuel pump is disclosed which simplifies present methods in that an integral casting of a portion of the housing has a valve chamber and a pulsator chamber cast therein having a common wall. A restricted port is provided by drilling through the wall, access for a drill being had through an open end of the casting. Most modifications show the previously described method. Completion of the fuel pump is accomplished by securing another casting to the previously described casting at the open end. Other modifications are disclosed wherein a restricted port is provided in an insertable disc force fitted intermediate the valve chamber and pulsator chamber to effect the common wall.

SHEET 1 OF 2

METHOD OF MANUFACTURING FUEL PUMPS

This application is a division of an application by the same inventor, Ser. No. 889,831 filed Dec. 24, 1969, abandoned, and which in turn was a division of an application filed by the same inventor, Ser. No. 566,504, filed July 20, 1969, abandoned, of which a continuation by the same inventor Ser. No. 833,856 filed May 29, 1969 became U.S. Pat. No. 3,530,991.

It has been found that the efficiency of a fuel pump is enhanced by the use of a restricted port between the inlet passage and a pulsator chamber and can still be further enhanced by effecting a restricted port between the outlet passage and the pulsator chamber. Such passages are actually part of the respective valve chambers of the pump.

Various objects and features of the invention will be apparent from the description which follows taken in conjunction with the appended drawing in which:

FIG. 1 is a fragmentary illustration in cross sectional elevation of one form of the invention taken on section line 1—1 of FIG. 3;

FIG. 2 is a cross sectional elevation through 2—2 of the view shown in FIG. 3;

FIG. 3 is a perspective of this form of the invention;

FIG. 4 is a cross section in elevation through 4—4 of FIG. 6; and

FIG. 5 is a cross section in elevation through 5—5 of FIG. 6.

FIG. 6 is a perspective of another modified form of pump with the fuel casting at the top of the assembly.

FIGS. 1 through 6 illustrate other embodiments of pumps using restricted inlet ports to air chambers for both the inlet and outlet sides of the pumps illustrated. A particular feature of the pumps shown in FIGS. 1—6 is that of ready reversibility wherein the fuel casting may be mounted at the top or bottom of the pump as related to an automobile engine. Thus, the comparison of FIGS. 3 and 6, showing perspectives, will make this clear.

The fuel castings are identical, as are the body castings, and the only distinction, insofar as determining whether a pump of the general construction shown is to be used in inverted position, is merely a matter of where the restricted ports for the pulsator chambers are located with relation to the vertical dimension of the chambers.

A very important manufacturing economy thus results since all castings are identical and all assemblies are identical and determination of pump mounting orientation is merely a matter of drilling holes through a wall common to the fuel passages and the respective pulsator chambers.

For example, comparison of FIGS. 1 and 4 will make it apparent that FIG. 21 is merely an inverted mirror image of FIG. 1 except that the restricted port 120 is located just above the inlet valve 125 in FIG. 1 for the inlet pulsator chamber 130 wherein in FIG. 4 the restricted port 120' is located near the bottom of the pulsator chamber 130.

In each instance, the restricted ports are effected by drilling in the casting through a wall such as 133 which is common to the inlet cavity 136 and the pulsator chamber 130. Such drilling is readily accomplished through the inlet (FIG. 4) or outlet (FIG. 5) or through the valve openings (FIGS. 1,2) before valve insertion. An open bore at the top of the pulsator chamber, ef-

fected in the casting process is for chip cleaning and mold coring, which opening is then plug-closed as by a force fitted disc 140 suitably pressed and swaged in place as shown, after the pulsator port has been drilled.

The very considerable manufacturing economy will be evident from the above description, in that all castings are made the same, with an open-ended pulsator chamber bore, and such castings can be stored ready for drilling pursuant to demand for particular mounting.

In the same manner, comparison of FIGS. 2 and 5 will make it apparent that the outlet cavities 143 have a common wall 146 with the outlet pulsator chambers 150 and, accordingly, drilling a restricted port such as 155 through the common wall as shown in FIG. 2, or a restricted port 160 as shown in FIG. 5, determines the relative position of the assembled pump with respect to an engine.

The fuel castings are die cast in the configuration shown in FIGS. 3 and 6, FIG. 6 merely showing the inverted position of FIG. 3. It is obvious that the same size bores and plugs 140 can be used for both inlet and outlet pulsator chambers.

Thus, each fuel casting comprises an inlet port leading to the inlet cavity and an outlet port leading from the outlet cavity, each such cavity having a pulsator chamber with a common wall therebetween. The symmetrical arrangement of the cavities and the pulsator chambers will be clear from FIGS. 3 and 6 thereby producing a pump which is relatively easy to cast and of smooth and pleasing appearance.

The valves such as valve 125 are identical for both inlet and outlet sides of the pump and are set into the inlet and outlet cavities through the open pump chamber 165 during assembly with the body casting 170 in a well-known manner. The valves are held by force fit and supported on ribs 175 disposed longitudinally on the walls of the cavities, there being a plurality of such ribs wherein the valves are pushed against the radially extending ends thereof.

The actuation is effected in a fully conventional manner as by a reciprocal stem and diaphragm as shown.

I claim:

1. A method of manufacturing a pump having a pair of body members which comprises casting a pump body member with a pair of adjoining cavities to effect a valve chamber and a pulsator chamber with a common wall therebetween; wherein at least one of said cavities has an opening accessible to a drill; drilling a hole through said common wall to effect communication between said cavities;

wherein said cavities have openings at opposite ends of the casting, one such opening being at an interior face of said casting; inserting a valve therein to effect a valve chamber; the other opening being at the exterior end of said casting, closing said latter opening to effect a pulsator chamber; and securing a second body member to said first-mentioned body member with a pump diaphragm between said body members to effect a pumping chamber exposed to said valve.

2. A method of manufacturing a pump having a pair of body members which comprises casting a pump body member with a pair of adjoining cavities to effect a valve chamber and a pulsator chamber with a common wall therebetween; wherein at least one of said cavities has an opening accessible to a drill; drilling a

hole through said common wall to effect communication between said cavities;

including casting an additional pair of adjoining cavities to effect another valve chamber and another pulsator chamber with a common wall wherein the chambers of each pair are open at opposite ends; drilling a hole through said latter common wall; inserting an inlet valve in one said valve chamber and

an outlet valve in the other said valve chamber; securing a second body to said first-mentioned body member with a pump diaphragm therebetween to effect a pump chamber exposed to said valves; and closing the open end of each said pulsator chamber.
